[57] CLAIM

[21] Appl. No.: **84,061**

The ornamental design for a game machine, as shown and described.

[22] Filed: **Feb. 24, 1998**

DESCRIPTION

[30] Foreign Application Priority Data

Aug. 29, 1997 [JP] Japan 9-66192

FIG. 1 is a prespective view of a game machine showing our new design;

[51] LOC (6) Cl. **21-01**

FIG. 2 is a front view thereof;

[52] U.S. Cl. **D21/326**

FIG. 3 is a rear view thereof;

[58] Field of Search D21/324-327,

FIG. 4 is a left side view thereof;

D21/811; 463/30.1, 46, 47, 49, 50, 51,

FIG. 5 is a right side view thereof;

58; 273/148 B

FIG. 6 is a top view thereof;

[56] References Cited

FIG. 7 is a bottom view thereof;

U.S. PATENT DOCUMENTS

FIG. 8 is a sectional view taken along the line 8—8 in FIG. 2;

D. 318,073 7/1991 Jang D21/326

FIG. 9 is a sectional view taken along the line 9—9 in FIG.

D. 376,391 12/1996 Okumura D21/326

2; and,

D. 380,779 7/1997 Shinzato D21/326

FIG. 10 is a sectional view taken along the line 10—10 in

D. 392,688 3/1998 Isetani et al. D21/326

FIG. 5.

D. 392,689 3/1998 Muraki et al. D21/326
